UNITED STATES PATENT OFFICE.

FRANK DIEMER, OF NIAGARA FALLS, NEW YORK.

SHOE.

SPECIFICATION forming part of Letters Patent No. 654,388, dated July 24, 1900.

Application filed May 4, 1900. Serial No. 15,478. (No model.)

To all whom it may concern:

Be it known that I, FRANK DIEMER, a citizen of the United States, and a resident of Niagara Falls, in the county of Niagara and State of 55 New York, have invented a new and useful Improvement in Shoes, of which the following is a specification.

This invention has the object to reinforce that portion of the shoe which incloses the 10 ankle of the wearer and to provide at the same time a convenient pocket on the inner side of the upper in which money, shoe-laces, and other articles of small bulk may be carried. To that end the upper is provided with 15 an interlining which is arranged between the upper and the lining and which is so constructed and secured that it reinforces the upper and also forms a convenient pocket.

In the accompanying drawings, Figure 1 is 20 an inside elevation of my improved upper spread out. Fig. 2 is a detached view of the interlining. Fig. 3 is a vertical section in line 3 3, Fig. 1. Fig. 4 is a similar section of the top portion of the upper on an enlarged 25 scale. Fig. 5 is a vertical section in line 5 5, Fig. 1. Fig. 6 is a similar section of the top portion of the upper on an enlarged scale. Fig. 7 is a horizontal section in line 7 7, Fig. 1. Fig. 8 is a fragmentary horizontal section 30 of the front of the upper on an enlarged scale. Fig. 9 is a fragmentary horizontal section of the heel-joint of the upper on an enlarged scale.

Like letters of reference refer to like parts 35 in the several figures.

A represents the upper of a shoe, which may be a man's or woman's lace or button shoe, that shown in the drawings being the upper of a lace-shoe having at its front a the 40 usual eyelets b for the reception of the laces and at its middle the usual upright heel seam or joint c.

D represents the lining, of well-known form and made, as usual, of a suitable fabric. E 45 represents an interlining of similar material which is arranged between the upper A and the lining D on both sides of the heel-seam c. This interlining extends at the rear from the top f of the upper along the heel-seam c to 50 the bottom of the upper and along the bottom or sole forwardly a suitable distance—

preferably, as shown, about as far as the width of the top of the upper. The interlining extends at the front along the front of the upper to the lower end of the facing g at 55 the inner side of the front and upwardly for a short distance along the inner edge of the facing and then down to the bottom or sole. The interlining E is thus composed of a main portion e, which extends from the top to the 60 bottom of the upper, and a front extension e', which extends to the lower end of the front of the upper, as clearly shown in Fig. 2 and by the dotted line 10 in Fig. 1. The interlining is secured at the heel by the usual 65 seams, at the bottom or sole by the usual stitching or other fastening devices, and at the front by the usual seams and eyelets or other fastening devices by which the lining D is secured, so that the interlining forms an 70 additional stiffening for the upper and reinforces the same. This renders the ankle, heel, and front portion of the upper somewhat more substantial and enables the same to better retain its shape. This interlining 75 E is secured at the top to the doubled top edge of the upper by a seam h, as shown on the left-hand side of Fig. 1 and in Figs. 3 and 4. The lining D is not secured at the top to the upper except at the front and rear, leaving the upper edge of the lining unattached between the front of the upper and the heel-seam. The interlining and the lining are secured together at a suitable distance below 80 the top edge of the upper by a seam k, so 85 that the portions of the lining and interlining above this seam form a pocket of a size and form which is suitable to contain money, shoe-laces, and other small articles, the unattached top portion of the lining forming 90 the mouth of the pocket.

If desired, the upper may be provided at its top with a flap L, of fabric or other suitable material, adapted to cover the mouth of the pocket, as shown on the right-hand side 95 of Fig. 1 and in Figs. 5 and 6. This flap is secured at its top, together with the upper edge of the interlining, to the doubled top edge of the upper by a seam l.

The interlining constructed and secured as 100 described adds but a trifle to the cost of the shoe and renders the shoe more sightly and

durable, reinforcing the upper, and at the same time provides the convenience of inside pockets in the upper.

I claim as my invention—

- 5 The combination with the upper, of an interlining which is secured at its top edge to the top edge of the upper and which extends from the top edge of the upper downwardly along the front of the upper and along its heel-joint, and a lining which is arranged on the inner side of the interlining and which is
- 10

unattached to the interlining at its top edge, to form the mouth of a pocket, and attached to the interlining at a suitable distance below its top edge to form the bottom of a ¹⁵ pocket, substantially as set forth.

Witness my hand this 2d day of May, 1900.

FRANK DIEMER.
